UNITED STATES PATENT OFFICE.

ERNEST H. SHAFF, OF GRAND HAVEN, MICHIGAN.

SUITCASE LOCK CONSTRUCTION.

1,408,909.

Specification of Letters Patent.

Patented Mar. 7, 1922.

Application filed January 28, 1919, Serial No. 273,660. Renewed September 16, 1921. Serial No. 501,148.

To all whom it may concern:

Be it known that I, ERNEST H. SHAFF, a citizen of the United States of America, residing at Grand Haven, in the county of 5 Ottawa and State of Michigan, have invented certain new and useful Improvements in Suitcase Lock Constructions; and I do hereby declare the following to be a full, clear, and exact description of the invention, such 10 as will enable others skilled in the art to which it appertains to make and use the same.

This invention relates to a suit case lock construction being particularly concerned 15 with novel structural features and combinations of elements in a device of that character whereby the manufacture is simplified and cheapened, and the use of a flat key instead of the usual round key, facilitated and 20 made more practically effective. This application relates to my former application for patent which resulted in United States Patent No. 1,265,534, issued May 7, 1918 for suitcase lock.

25 For an understanding of the invention and the constructions whereby the above enumerated advantages are attained together with many others not at this point specifically enumerated, reference may be 30 had to the following description taken in connection with the accompanying drawing, in which,

Fig. 1 is a front elevation of the lock.

Fig. 2 is a similar view, the key guide 35 member being removed from the lock.

Fig. 3 is an enlarged fragmentary vertical section through the lower part of the lock.

40 Fig. 4 is an enlarged fragmentary front elevation of the lock case and the dished washer which forms one element of the key guide.

Fig. 5 is a plan view of the inner lock mechanism and the retaining housing therefor, the same being located under the lock case in assembled form, and

Fig. 6 is a side elevation of the outer member of the key guide.

Like reference characters refer to like 50 parts in the different views of the drawing.

The lock mechanism is housed within a casing pressed from thin sheet metal, having a rectangular outline as indicated at 1 and formed with a raised middle portion 2 55 which adjacent its lower end has a relatively large rectangular opening 3 cut

therein while a circular opening 4 is formed in the upper part of said raised portion 2 of the case, through which the tongue on the hasp attached to the cover of the suit 60 case may pass in the usual manner to engage with the locking mechanism of the lock.

The locking mechanism is located in the raised portion 2 of the case resting on and being retained in position by a metal plate 65 5 which has oppositely projecting ears 6 to pass immediately below the case 1 at each side of the raised portion 2 thereof. A hole 7 is made in each ear through which inwardly pressed projections 8 of the metal of 70 the case may be inserted and headed over to hold the plate in fixed relation to the case. Any other suitable means of fastening plate 5 in place may be used if desired.

The locking mechanism includes a plate 75 9 slidably mounted on and above the plate 5 and having portions cut away and pressed inwardly as indicated at 10 to pass and engage with the hasp tongue. A leaf spring 11 held at one end between tongues 12 80 turned up from the plate 5, bears at its free end against the plate 9 tending to force it against the upper end of the retaining plate. A locking bolt 13 formed with a notch 14 in its lower edge is mounted between turned up lugs 15 on the locking plate 9 and may be moved from the position shown in Fig. 5 so that one end thereof comes behind the turned in flange 16 on plate 5, thus locking the locking plate 9 85 against downward movement. The movement of the locking bolt is performed by engagement of a key with the bolt in the notch 14 thereof.

A key guide and opening covering member is attached to the lower end of the locking plate 9. It comprises a small housing 17 substantially square in form, from each side of which inwardly extending projections 18 are made which terminate in tangs 19. The projections 18 pass through the opening 3 and engage against the plate 9, the tangs 19 passing through holes 20 made in spaced apart relation in the lower part of the locking plate 9, it being apparent that 105 this housing 17 is movable with the locking plate and that it substantially covers the opening 3 in the lock case. A circular opening 21 having a slot extension 22 is made in the face of the housing 17 as shown.

110 Within the housing 17, a dished washer 23 is located, the same having a central portion

24 which enters the circular opening 21 in the housing 17. This washer is turned downwardly and outwardly to bear against the front of the raised portion 2 of the lock case and at its outer edges is formed with an annular lip 25 to make a firm bearing irrespective of the position of the washer when the locking plate 9 is moved. The washer is of sufficient width to pass over the 10 opening 3 and bear firmly against the part 2 at both sides of the opening, this permitting the cutting away of all the metal shown instead of slots merely to pass the extensions 18 and an opening for the passage of 15 the key as usual heretofore, greatly reducing the die cost and the cost of manufacture. A slot 26 is cut in the washer for free passage of the key to actuate the locking bolt.

From the foregoing, it is apparent that I 20 have made improvements in suit case locks which facilitate the employment of flat keys for actuation of the locks and which reduces the manufacturing costs below what they would otherwise be. The structure described 25 is in actual use and has proved particularly satisfactory for the purposes described.

I claim:

1. In a suit case lock, a lock case having a 30 raised middle portion provided with an elongated opening therein adjacent one end of said raised portion, locking mechanism including a locking plate located within the lock case, said locking plate being mounted for slidable movements, a housing having a 35 key passing opening therein located against

the outer side of the lock case and provided with inward extensions at each side thereof passing through said opening in the case and secured to the movable locking plate, and a dished washer located within the housing 40 and also provided with a key passing opening, said washer bearing at its edges against the front face of the lock case both above and below the opening therein.

2. In a suit case lock, a lock case, locking mechanism including a movably mounted locking plate located within the lock case, a raised housing provided with an upper circular opening and with a downwardly extending slot in conjunction with the circular opening located over the central lower portion of the lock case, said housing having inward extensions passing through the lock case and connected to the movable locking plate, the passage of the extensions through the lock case permitting movement of the housing with the lock plate, a dished washer located within the housing and having a raised portion entering the upper circular part of the opening in the housing, said 60 washer having a slot therein through said raised portion and the adjacent portion which aligns with the slot portion of the opening in the housing, and an annular out-turned lip at the edges of the washer bearing against the front of the lock case, substantially as described.

In testimony whereof I affix my signature.

ERNEST H. SHAFF.
